AUTOMATIC COIN-CONTROLLED ELECTRICALLY OPERATED STEP-BY-STEP MECHANISM

Robert R. Witherell, Bloomington, Ill., assignor to Williams Oil-O-Matic Heating Corporation, Bloomington, Ill., a corporation of Illinois

Application May 5, 1938, Serial No. 206,115

8 Claims. (Cl. 194—10)

This invention relates to improvements in automatic coin-controlled electrically operated step-by-step mechanism particularly adapted for use in connection with a cabinet for containing and vending articles one at a time after the depositing of a coin therein.

With these and other objects in view, reference is made to the accompanying sheets of drawings which illustrate a preferred embodiment of this invention with the understanding that detail changes may be made without departing from the scope thereof.

Figure 1 is a view partly in elevation and partly in section of the motor housing and casing containing the motor operated and coin-controlled mechanism in position upon a dispensing cabinet containing a rotatable turn table which is advanced one step each time the motor operates in response to the depositing of a coin in the casing.

Figure 2 is a view in section of the coin-controlled and switching mechanism taken on the line 2—2, Figure 1, looking in the direction of the arrows, showing the positions assumed by the parts before a coin has closed the first switch.

Figure 3 is a similar view taken on the line 3—3 of Figure 1, looking in the direction of the arrows, showing the reverse side of the switch carrying plate and a coin having been received to close the first switch.

Figure 4 is a detail view in section taken on the line 4—4, Figure 1, looking in the direction of the arrows, showing the position assumed by the parts after the pin 10 has been rotated through 180 degrees.

Figure 5 is a fragmentary detail view in section taken on the line 5—5, Figure 1, looking in the direction of the arrows, showing the relation of the cams and indexing pin after both switches have been closed.

Figure 6 is a fragmentary detail view taken in section on the line 6—6 of Figure 1, looking in the direction of the arrows.

Figure 7 is a schematic diagram illustrating the switches and their wiring connections to each other and to the motor illustrating the first switch closed by the reception of a coin and the second switch open.

Figure 8 is a similar view illustrating the first switch open by the release of the coin shown in Figure 7 and the second switch closed by the rotation of its operating cam.

In the embodiment of the invention illustrated, a motor M is mounted in a housing 1 supported at right angles to a casing 2, having a removable cover 3, for mounting a coin receiving, selecting,

and positioning mechanism of commercial form. The motor housing 1 extends below the motor to enclose a train of gears for operating a step-by-step mechanism. As shown in Figure 1, the casing 2 engages the side 4 of a dispensing cabinet with the motor housing resting upon the top 5 thereof with the step-by-step operating mechanism passed through an aperture 6 provided in the top. In this type of dispensing cabinet a rotatable turn table 7 is mounted to support the articles to be dispensed and advance them step by step to the dispensing aperture in the cabinet. In this form the turn table is provided with a scalloped periphery formed by similar concentric concave arcs 8 equally spaced apart between similar radial slots 9, as shown in Figure 4. The step-by-step mechanism includes an indexing pin 10 mounted upon a disc 11 secured to the lower end of a sleeve 12 rotatably mounted and retained upon a stud 13 depending from the under side of the motor housing 1. The pin 10 is located on the disc 11 in such a manner that each time the disc is rotated, the pin is engaged in a radial slot 9 and imparts a step in the movement of the turn table. As shown in Figures 1, the plate 11 is arranged below the periphery of the turn table 7, and in order to lock the turn table against movement after it has been disengaged by the pin 10, a similar plate 11^a is provided having an integral depending spacer 14 concentric with the plate 11 and having a radius concentric with the radius of the arcuate scallops 8. The plate 11^a is provided with an aperture passing therethrough for receiving the pin 10, and the spacer 14 is provided with an arcuate cut-out portion 15 so arranged that when the pin 10 is received in the aperture and the pin-carrying disc 11 is rotated, the plate 11^a will rotate therewith and be positioned above the periphery of the turn table 7 with the spacer 14 resting upon the upper surface of the plate 11 so that when both plates are rotated, the cut-out portion 15 will allow the apex formed between the arcuate scallop 8 and radial slot 9 to pass into said cut-out space and allow the pin 10 to pass into the radial slot and engage the turn table 7 to advance the turn table therewith. The cut-out space 15 will allow the apex formed by the opposite side of the radial slot 9 and contiguous scallop 8 to pass thereinto and after the pin 10 has passed from engagement after imparting a step to the turn table, the cylindrical surface of the spacing member 14 will wipe over the arcuate surface of the contiguous scallop 8 and will prevent further rotation of the turn table until it is again engaged by the pin 10.

The motor shaft 16 is extended below that portion of the housing 1 supporting the motor and is connected by a train of gears G to a gear 17 rotatably mounted upon the sleeve 12. Two cams 18 and 19 are keyed upon the sleeve 12 for longitudinal movement thereon and are held in engagement with the gear 17 by a cylindrical fibre clutch member 20 interposed upon the sleeve 12 between the gear 17 and cam 18 by a coil spring 21 positioned about the sleeve 12 with one end bearing upon the under side of the cam 19 and the other end anchored to an abutment 22 secured upon the sleeve 12. The disc 11^a, when positioned to receive the pin 10, is held with its spacing member 14 in engagement with the disc 11 by a coil spring 23 interposed about the sleeve 12 between the abutment 22 and upper side of the disc 11^a.

The clutch 20 allows a sliding of the gear 17 in the event that the turn table becomes jammed before the motor ceases to operate, and preventing damage to the train of gears or the step-by-step mechanism. The lifting of the disc 11^a out of engagement with the pin 10 to remove the spacing member 14 from contact with the periphery of the scalloped edge of the turn table will allow the turn table to be rotated independently of the step-by-step mechanism in order to refill the cabinet.

As heretofore said, a coin receiving, directing, and positioning mechanism of commercial form is mounted within the casing 2 in which the spaced-apart plates 24 and 25 form a part of said mechanism. As shown in Figure 2, a coin is directed to strike upon an anvil 26, forming a part of said commercial mechanism, and be directed from there between a pin 27, which has been added to the mechanism and an abutment 28, which forms a part of the said commercial mechanism, into a coin chute formed by the portion 29 along one edge of the plate 24, which also forms a part of the commercial mechanism, and a member 30 mounted upon a pivot 31 between the plates 24 and 25 which has been added to the commercial mechanism. This member is provided with an upper angular extension 32 and normally held in engagement with the upper side of the abutment 28 by the weight of an extension 33 from that side of the member 30 adjacent the pivot 31 as to cause the lower end 34 to form the other side of the coin chute and direct a coin passing between the pin 27 and upper end 32 of the member 30, as shown in dotted lines, to rotate the lower end 34 of the member 30 and position and the coin to rest upon the end of the end 35 of a switch operating lever 36 and against the end 37 of a retractable rod 38 which projects into the path of the coin, as shown in dotted lines in Figure 2.

When a coin has been received in the position above described, and as shown in Figure 3, the rotation of the member 31 causes the angular end 32 to restrict the space between the abutment 28 and pin 27 so that as long as a coin remains in engagement with the switch operating lever 36 and end 37 of the rod 38, other coins deflected by the anvil 26 will strike the pin 27 and end 32 of the member 30 and be ejected or returned to the operator, as shown in dotted lines in Figure 3. The extension 33 is provided with a pin 39 which extends through an arcuate slot 40 provided in the mechanism plate 25 for a purpose hereinafter described.

The switching mechanism operated by the lever 36 is shown in Figures 2 and 3. The lever 36 is

pivoted and normally weighted by the end 41 to maintain the switch in open position with its free end 35 in position to be depressed by the weight of a coin to close the switch, as shown in Figure 2. The switching mechanism shown includes a resilient contact member 42 adapted to be engaged by the end 41 of the operating lever 36 and is normally spaced apart from a contact member 43 whereby the depression of the end 35 of the operating lever will cause the contacts to engage and make an electrical connection, as shown in Figure 3. Referring to the schematic diagram of Figure 7, it will be seen that when this switch is closed, a circuit will be completed from the commercial line L through the wire 44, contacts 43 and 42, wire 45, through the motor M, and by wire 46 back to the commercial line L'. The closing of the switch by the coin will then initiate operation of the motor which, through the train of gears, will impart a rotation to the sleeve 12 and cams 18 and 19 thereon. The rod 38 is bent upward from its end 37 and then bent again to pass through a bracket 47 secured upon the under side of the housing 1 to direct the end of the rod 38 to engage the surface of the cam 18 and is preferably maintained in engagement therewith by a spring 48 surrounding the rod 38 bearing at one end against the bracket 47 and the other against an abutment 49 upon the rod. A second circuit connected in parallel to the first circuit is closed by a switch 50 mounted in the bracket 47 below the rod 38 to cause a reciprocating operating member 51 to normally engage the surface of the cam 19. This switch, as shown in Figures 7 and 8, includes spaced apart contacts 52 and 53 with wire 54 connecting contact 52 to wire 44 and contact 53 connected by wire 55 to wire 45. A connecting member 56 is normally held out of engagement with contacts 52 and 53 by the spring pressed plunger 51 and when the plunger 51 is depressed by the cam 19, the connection is made between contacts 52 and 53, as shown in Figure 8, establishing a parallel circuit through the motor about open contacts 42 and 43.

The cam formation and relation of the cams 18 and 19 and pin 10 is shown in Figures 5 and 6 to be such that when a coin is deposited, the end 37 of the rod 38 will be extended into the coin chute to retain the coin to close the first switch, and after the energization of the motor has operated the sleeve 12 to advance the pin 10 in the direction of the scalloped periphery of the turn table, the second switch will be closed by the cam 19 and thereafter the circuit through the first switch will be opened by the cam 18, withdrawing the end 37 of the rod 38 from engagement with the coin and allowing the coin to roll off the end 35 of the switch operating lever 36 into a coin receptacle. After the coin has been released from the switch-operating lever 36, and after the pin 10 has imparted a complete step of the movement to the turn table 7, the cam 19 will allow the second switch to open so that the motor will be de-energized and the cam 18 will again insert the end 37 of the rod 38 in the path of the next coin to be deposited in the mechanism.

It is preferable to provide a brake drum 57 upon the motor shaft 16 to be engaged by an adjustable brake member 58 to prevent coasting of the motor after the circuit has been broken from carrying the pin 10 beyond a predetermined distance so that upon next operation of the motor, the pin 10 will engage the radial slot 9 to impart the next movement to the turn table.

Means is also provided to render the step-by-

step mechanism inoperative after the turn table has been rotated by the step-by-step mechanism to place the last article in position to be dispensed. To accomplish this, a rod 59 is mounted to rotate in a bearing provided thereon on the under side of the housing 1 with an end 60 bent to support an operating member 61 in the path of a lug or cam 62 carried upon the turn table 7 in such a position that as the turn table approaches a position to dispense the last article, the abutment 62 will engage the member 61 and impart a rotation to the rod 59. The other end 63 of the rod 59 is extended upwardly at an angle to the rod 59 and parallel with the adjacent face of the plate 25 to engage the under side of the pin 39 upon the extension 33 of the member 30 when the rod 59 is rotated to lift the pin 39 and rotate the member 30 about its pivot 31 into the position shown in Figure 3. This is the position normally assumed by the member 30 when a coin has closed the first switch, and, therefore, after the turn table has dispensed its last article, the depositing of a coin after the cabinet is empty will be deflected by the pin 27 and end 32 of the member 30, as shown in Figure 3. It is preferable to provide a stop 64 upon the plate 25 to support the end 63 of the rod 59 when the operating member 61 is in position to be engaged by the abutment 62.

It is readily seen from the above construction that a vending machine embodying this invention will be entirely automatic; that is, whenever a coin is deposited in the aperture provided therefor in the mechanism casing, an article will be dispensed from the cabinet by the operation of the electrically operated step-by-step mechanism. Furthermore, that when the last article has been dispensed, coins which may be deposited thereafter will be returned to the prospective purchaser.

Furthermore, the particular mechanism disclosed herein provides means as soon as one coin has been deposited, and been received in the coin chute for initiating operation of the step-by-step mechanism, to reject and return other coins deposited thereafter until the first coin has been released, and allow the next deposited coin to again operate the mechanism after it has completed one full step in the vending of an article. Prospective purchasers sometimes place several coins in a coin-controlled mechanism, one right after the other, in the expectation that the vending machine will successively present the number of articles corresponding to the number of coins inserted. In such an event, the present invention contemplates the prevention of the possibility of coins deposited quickly one after the other from jamming the coin-controlled mechanism and will reject all coins deposited after the first one and return the coins to the prospective purchaser until the mechanism is ready to initiate another cycle. The above described step-by-step mechanism provides a very simple and positive means for locking the turn table after each operation as well as a simple means for releasing the coin which closes the first switch to initiate operation of the motor by the operation of the motor itself thereafter closing a second switch in a parallel circuit to continue the operation of the mechanism until the step initiated by the depositing of a coin has been completed.

What I claim is:

1. A coin actuated electrically operated step-by-step mechanism for a dispensing cabinet having a rotatable turn table for dispensing arti-

cles therefrom, an electric motor having a drive shaft for rotating said turn table to present said articles in position for dispensing upon completion of a cycle of operation thereof, a pair of normally open switches connected in parallel in the motor circuit, a tiltable arm actuated by the weight of a coin thereon for closing one of said normally open switches to initiate operation of said electric motor, means for directing said coin to said tiltable arm, means for releasably retaining said coin on said arm, a cam mounted on said driving shaft, means actuated by said cam for closing the other of said normally open switches, a second cam mounted on said driving shaft, and means including said second cam for releasing said coin from said tiltable arm and thereby permitting automatic operation of said first mentioned switch into a normally open condition after said second mentioned switch has been operated into a closed condition to maintain operation of said motor, said first mentioned cam operating said last mentioned switch into a normally open condition upon completion of a cycle of operation.

2. A coin actuated electrically operated step-by-step mechanism for a dispensing cabinet having a rotatable turn table for dispensing articles therefrom, an electric motor having a drive shaft for rotating said turn table to present said articles in position for dispensing upon completion of a cycle of operation thereof, a pair of normally open switches connected in parallel in the motor circuit, a tiltable arm actuated by the weight of a coin thereon for closing one of said normally open switches to initiate operation of said electric motor, means for directing said coin to said tiltable arm, means for retaining said coin on said tiltable arm to maintain said closed circuit condition, a cam mounted on said driving shaft, means actuated by said cam for closing the other of said normally open switches, a second cam mounted on said driving shaft, and means actuated by said second cam to operate said coin retaining means for releasing said coin and thereby the weight thereof from said tiltable arm for operating said first mentioned switch into a normally open condition after said second mentioned switch has been operated into a closed condition to maintain operation of said motor, said first mentioned cam operating said last mentioned switch into a normally open condition upon completion of a cycle of operation.

3. A coin actuated electrically operated step-by-step mechanism for a dispensing cabinet having a rotatable turn table for dispensing articles therefrom, an electric motor having a drive shaft for rotating said turn table to present said articles in position for dispensing upon completion of a cycle of operation thereof, a pair of normally open switches connected in parallel in the motor circuit, means actuated by engagement of a coin therewith for closing one of said normally open switches to initiate operation of said electric motor, means for directing said coin to said actuating means, means for releasably retaining said coin on said actuating means, said coin directing means being movable to obstruct the path of a second coin upon engagement of a first coin with said actuating means, a cam mounted on said driving shaft, means actuated by said cam for closing the other of said normally open switches, a second cam mounted on said driving shaft, and means including said second cam for releasing said coin from said actuating means and thereby permitting automatic opera-

tion of said first mentioned switch into a normally open condition after said second mentioned switch has been operated into a closed condition to maintain operation of said motor, said first mentioned cam operating said last mentioned switch into a normally open condition upon completion of a cycle of operation.

4. A coin actuated electrically operated step-by-step mechanism for a dispensing cabinet having a rotatable turn table for dispensing articles therefrom, an electric motor having a drive shaft for rotating said turn table to present said articles in position for dispensing upon completion of a cycle of operation thereof, a pair of normally open switches connected in parallel in the motor circuit, means actuated by engagement of a coin therewith for closing one of said normally open switches to initiate operation of said electric motor, a pivotally mounted member bounding a portion of a passage for directing said coin to said actuating means, means for releasably retaining said coin on said actuating means, said member occupying normally such a position as to present a free passage for a coin at the entrance to said passage and being movable to a second position to obstruct the entrance to said passage by the engagement of a coin therewith on the other side of the pivotal point thereof, a cam mounted on said driving shaft, means actuated by said cam for closing the other of said normally open switches, a second cam mounted on said driving shaft, and means including said second cam for releasing said coin from said actuating means and thereby permitting automatic operation of said first mentioned switch into a normally open condition after said second mentioned switch has been operated into a closed condition to maintain operation of said motor, said first mentioned cam operating said last mentioned switch into a normally open condition upon completion of a cycle of operation.

5. A coin actuated electrically operated step-by-step mechanism for a dispensing cabinet having a rotatable turn table for dispensing articles therefrom, an electric motor having a drive shaft for rotating said turn table to present said articles in position for dispensing upon completion of a cycle of operation thereof, a pair of normally open switches connected in parallel in the motor circuit, a tiltable arm actuated by the weight of a coin thereon for closing one of said normally open switches to initiate operation of said electric motor, means for directing said coin to said tiltable arm, a movable rod co-operating with the end of said tiltable arm for retaining the coin in position thereon, a cam mounted on said driving shaft, means actuated by said cam for closing the other of said normally open switches, and a second cam mounted on said driving shaft for moving said rod out of its co-operative relation with said tiltable arm for releasing said coin and for operating said first mentioned switch into a normally open condition after said second mentioned switch has been operated into a closed condition to maintain operation of said motor, said first mentioned cam operating said last mentioned switch into a normally open condition upon completion of a cycle of operation.

6. A coin actuated electrically operated step-by-step mechanism for a dispensing cabinet having a rotatable turn table for dispensing articles therefrom, an electric motor having a drive shaft for rotating said turn table to present said articles in position for dispensing upon completion

of a cycle of operation thereof, a pair of normally open switches connected in parallel in the motor circuit, means actuated by engagement of a coin therewith for closing one of said normally open switches to initiate operation of said electric motor, means for directing said coin to said actuating means, means for releasably retaining said coin on said actuating means, said directing means including spaced plates having a stationary plate and a weighted pivotal member bounding a passage therebetween, said member being normally held angularly with respect to said stationary plate by the weight thereof with the smallest width of the passage therebetween less than the diameter of the coin whereby the movement of a coin therethrough will pivot said member and obstruct the entrance to said passage, a cam mounted on said driving shaft, means actuated by said cam for closing the other of said normally open switches, a second cam mounted on said driving shaft, and means including said second cam for releasing said coin from said actuating means and thereby permitting automatic operation of said first mentioned switch into a normally open condition after said second mentioned switch has been operated into a closed condition to maintain operation of said motor, said first mentioned cam operating said last mentioned switch into a normally open condition upon completion of a cycle of operation.

7. A coin actuated electrically operated step-by-step mechanism for a dispensing cabinet having a rotatable turn table for dispensing articles therefrom, an electric motor having a drive shaft for rotating said turn table to present said articles in position for dispensing upon completion of a cycle of operation thereof, a pair of normally open switches connected in parallel in the motor circuit, a substantially horizontally extending pivotal arm actuated by the weight of a coin thereon for closing one of said normally open switches to initiate operation of said electric motor, means for directing said coin to said pivotal arm including a pivotal member bounding one side of a substantially vertically extending passage in alignment with one end of said pivotal arm, a movable rod in the vertical path of movement of said coin through said passage co-operating with the end of said pivotal arm for retaining said coin in position thereon, said retained coin holding said member in a pivoted position to obstruct the entrance to said passage, a cam mounted on said driving shaft, means actuated by said cam for closing the other of said normally open switches, and a second cam mounted on said driving shaft for moving said rod out of its co-operative relation with said tiltable arm for releasing said coin and for operating said first mentioned switch into a normally open condition after said second mentioned switch has been operated into a closed condition to maintain operation of said motor, said first mentioned cam operating said last mentioned switch into a normally open condition upon completion of a cycle of operation.

8. A coin actuated electrically operated step-by-step mechanism for a dispensing cabinet having a rotatable turn table for dispensing articles therefrom, an electric motor having a drive shaft for rotating said turn table to present said articles in position for dispensing upon completion of a cycle of operation thereof, a pair of normally open switches connected in parallel in the motor circuit, means actuated by engagement of a coin therewith for closing one of said normally open

switches to initiate operation of said electric motor, means for directing said coin to said actuating means including a pivotal member bounding one side of a passage, means for releasably retaining said coin on said actuating means, a movable rod actuated by said rotatable turn table at a predetermined position thereof for pivoting said member to a position to obstruct the entrance to said passage, a cam mounted on said driving shaft, means actuated by said cam for closing the other of said normally open switches, a second cam mounted on said driving shaft, and

means including said second cam for releasing said coin from said actuating means and thereby permitting automatic operation of said first mentioned switch into a normally open condition after said second mentioned switch has been operated into a closed condition to maintain operation of said motor, said first mentioned cam operating said last mentioned switch into a normally open condition upon completion of a cycle of operation.

ROBERT R. WITHERELL.
